UNITED STATES PATENT OFFICE

OSWALD H. HANSEN, OF CEDARBURG, WISCONSIN, ASSIGNOR TO HANSEN CANNING MACHINERY CORPORATION, OF CEDARBURG, WISCONSIN, A CORPORATION OF WISCONSIN

CAN FILLING MACHINE

Application filed April 5, 1928. Serial No. 267,545.

The present invention relates in general to improvements in mechanism for measuring and delivering batches of material to a succession of receptacles, and relates more specifically to improvements in the construction and operation of machines for packing fibrous substances such as sauer kraut or the like, in containers.

A general object of the invention is to provide various improvements in the details of construction of kraut fillers or the like, which will permit simplification in the structure while at the same time enhancing the efficiency of such machines.

A more specific object of the invention is to provide improvements in kraut filler structure, which are especially applicable to machines such as disclosed in Patent No. 1,776,432, granted September 23, 1930. Some of the novel features of can filling machine structure, disclosed but not specifically claimed herein, form the subject of said patent and of Patents 1,726,297, granted August 27, 1929, and 1,750,467, granted March 11, 1930.

Other specific refinements constituting the present improvement may be generally defined as follows:—

The provision of more effective automatic kraut fibre feeding mechanism for delivering the material to the successive pockets of the measuring mechanism.

The provision of means for properly conditioning the kraut fibre prior to delivery thereof to the measuring pockets.

The provision of mechanism for effectively segregating the kraut delivered to the measuring pockets from that remaining in the supply chamber.

The provision of means for insuring proper filling of the measuring pockets with homogeneous batches of kraut.

The provision of improved motion transmitting mechanism for imparting movement to the various elements of can filling machines or the like.

The provision of an improved measuring plunger especially applicable to kraut measuring and feeding machines, and to other fillers adapted to handle similar substances.

A clear conception of the various features constituting the present invention and of the manner of constructing, assembling and operating machines built in accordance therewith, may be had by referring to the drawings accompanying and forming a part of this specification in which like reference characters designate the same or similar parts in the several views. 55

Fig. 1 is a central vertical section through the improved kraut filling machine, the section being taken through the kraut fibre feeding and measuring mechanism of the device. 60

Fig. 2 is a transverse vertical section taken 65 through the can supply mechanism and one of the measuring devices.

Fig. 3 is a full top view of the improved kraut filling machine.

Fig. 4 is a part sectional side elevation of 70 the kraut filler and of the apparatus for conditioning and for supplying the conditioned material to the machine.

Fig. 5 is a transverse horizontal section 75 through the improved filling machine, the section being taken just below the material measuring and feeding mechanism thereof.

Fig. 6 is a transverse horizontal section taken through the kraut measuring and feeding mechanism of the improved machine. 80

Fig. 7 is a development of the improved measuring mechanism showing the various positions assumed by the successive plungers during normal operation of the machine.

Fig. 8 is a top view of a modified form of 85 measuring mechanism especially applicable to kraut filling machines or the like.

Fig. 9 is a vertical section through the modified structure of Fig. 8.

Fig. 10 is a relatively fragmentary elevation of the machine, showing the details of construction of the kraut fibre severing mechanism. 90

Fig. 11 is a fragmentary section taken transversely through the kraut fibre feeding mechanism and chamber. 95

Fig. 12 is a part sectional top view of the measuring mechanism showing the details of construction of the plungers and of the plunger guiding and retaining means. 100

Fig. 13 is a fragmentary sectional view of the lower portion of one of the plungers.

Fig. 14 is a full bottom view of one of the plungers.

Referring generally to Figs. 1 to 6 inclusive, it will be noted that the improved kraut filling machine comprises in general, an annular series of measuring devices for automatically producing a succession of accurately measured batches of kraut and juice and for delivering the said batches in a downward direction; mechanism for automatically conditioning the kraut and the juice and for feeding the same to the measuring devices; can transporting mechanism for automatically conveying the cans through the machine; and motion transmission mechanism for driving the various elements of the machine.

The automatic measuring mechanism specifically shown in Figs. 1, 2, 3, 6, 7, 12, 13 and 14, consists of a stationary annular wall 10 having a bottom plate 9 formed integral therewith; a rotary member 48 snugly fitted for rotation within the wall 10 and having therein an annular series of measuring pockets 7; driving mechanism for intermittently advancing the pockets 7 about the central axis of the wall 10; a series of vertically movable plungers 8 disposed within the pockets 7; and mechanism for moving the plungers 8 during rotation of the member 48.

The annular wall 10 is rigidly mounted upon a stationary can support 128 which is secured to the main frame 28 of the machine, and has kraut and brine feed openings 5, 68 respectively, through the lower portion thereof just above the bottom plate 9. The brine inlet opening 68 is covered with a grid as shown in Fig. 2, and is in open communication with a supply pipe 40. The annular wall 10 is of different height at different points about the axis thereof, the upper end of the wall cooperating with plunger actuating tracks 45 to form rails for vertically moving the plungers 8, see Fig. 7. The rails thus produced are engaged by rollers 59 carried by the plungers 8, and the tracks 45 are vertically adjustable to vary the stroke of the plungers 8, by means of adjusting mechanism 46. The bottom plate 9 is provided with a relatively long material discharge opening 70 spaced vertically from the can support 128. The successive cans 55 are transportable about the axis of the main driving shaft 11 and directly beneath the bottom plate 9, by means of a series of can hooks 12, the cans being supported upon the auxiliary support 69 or directly upon the main can support 128.

The rotary pocket member 48 is secured to a main drive shaft 11 by means of a detachable driving connection 61, and may be constructed as shown in Fig. 12. The main body of the member 48 is provided with

radial arms which partially embrace the plungers 8, and which have plunger retainers 47 secured to the outer ends thereof by means of screws 51. The plunger retainers 47 snugly engage the bore of the wall 10 and 70 coat with detachable facings 49 of the plungers. The plunger facings 49 are detachably secured to the plungers 8 by means of screws 52, the upper of which also provide pivotal supports for the plunger actuating rollers 59. The lower faces of the plungers 8 are provided with slots 44 communicating with lateral holes 43, the latter being intermittently communicable with an air vent 42 shown in Fig. 1, during admission 80 of the kraut fibre to the successive pockets 7. A steam pipe 74 attached to the stationary wall 10 as shown in Fig. 6, may be utilized for the purpose of passing steam through the holes 43, slots 44 and pockets 7 in order to prevent clogging of the air vent and to maintain the structure clean. Both the pocket member 48 and the plungers 8, are freely vertically removable from the wall 10, and the plungers 8 may be likewise removed from 90 the pocket member 48.

Since kraut juice is extremely detrimental to close fitting bearings, it has been found desirable to construct the plungers 80 as shown in Figs. 8 and 9. These plungers 80 have a relatively loose fit within the pockets 7, this fit being confined to the lower portions of the plungers. The upper end of each plunger is provided with a top plate 73 which slidably engages a pair of parallel guide rods 71, 72 in order to insure parallel movement of the plunger, thus eliminating necessity of snugly fitting the plungers 80.

The automatic kraut fibre feeding mechanism consists of a casing forming a chamber 4 having its outer end communicating upwardly with a kraut supply hopper 2 and having its inner end communicating laterally with the opening 5 of the wall 10 as shown in Figs. 1 and 6. A plurality of simultaneously oscillatable and reciprocable fibre feeding fingers 6 project into the chamber 4 from opposite sides thereof, the fingers 6 being staggered as shown in Figs. 6, 11 and the rear fingers being confined toward the outermost portion of the chamber 4 in order to permit the entering kraut to settle to the bottom of the chamber. The bottom of the chamber 4 is formed as shown in Figs. 6 and 11, being provided with a plurality of drain openings or slots 41 beneath which is located a pocket 3 for catching the escaping juice. As shown in Fig. 4, the drainage pocket 3 may be connected with a treating tank 33 by means of a pipe 34.

The raking fingers 6 are slidably associated with oscillatory pivot blocks 79 supported by pivots 57, and have their outer ends pivotally associated with actuators 58 as shown in Figs. 3 and 6. The actuators 58 are gyratable by 130

means of cranks 64 secured to the upper ends of vertical shafts 62 as disclosed in Figs. 3, 6 and 11, and the shafts 62 are rotatable by means of spur gears 63 meshing with gears 23 as shown in Fig. 5. The gears 63, 23 are simultaneously rotatable to move the fingers 6, by means of a gear 22 secured to the upright counter shaft 21 and meshing with a gear 20 mounted upon the main driving shaft 16. The finger driving mechanism which is disposed above the can support 128 and on opposite sides of the chamber 4, is surrounded by suitable guard walls 56 in order to avoid injury to the operators. The inner ends of the fingers 6 are movable along looped paths within the chamber 4, so as to rake the admitted kraut fibre toward the opening 5 without tearing the fibres.

An oscillatory kraut fibre shearing knife 75 shown in Fig. 10 is located at the discharge opening 5 and is swingable in a vertical plane about a horizontal pivot at its upper end, by means of a bell crank 76 and connecting link to sever the fibre admitted to the measuring pockets 7 from that within the chamber 4, without tearing. The bell crank 76 is swingable back and forth in a vertical plane, by means of a gear 78 meshing with a pinion 77 secured to one of the shafts 62. The gear 78 is provided at its top with an annular cam groove having a laterally off-set portion which is intermittently engaged by a roller secured to the horizontal arm of the bell crank 76, to swing the crank and thereby move the knife back and forth.

The apparatus for treating the kraut prior to measuring and packing thereof, consists of a combined bleaching, exhausting and sterilizing tank 33 to which the kraut is delivered in bulk from the vats, see Fig. 4. The kraut fibre after being treated in the tank 33 is removed and elevated into the supply hopper 2 along a chute 35. The entrained liquid or juice admitted to the chamber 4 with the kraut fibre, drains into the pocket 3 from whence it is returned to the tank 33 through the pipe 34. A pump 38 is adapted to withdraw liquid from the bottom of the tank 33 through a strainer 50, and forces the removed liquid through a pipe 36 to a supply tank 31 located adjacent to the measuring mechanism. The kraut juice or brine passing through the pipe 36 may be heated by means of a steam heater 37, and the tank 31 may be provided with a strainer 39 in order to separate any fibre which may be admitted with the liquid. The upper portion of the supply tank 31 is provided with an overflow 32 leading to the treating tank 33, and the portion of the tank 31 below the strainer communicates with the pipe 40 which communicates with the measuring mechanism.

The empty cans 55 are delivered to the machine by means of a can chute 53 and a tapered can feed drum 29 the latter of which

is adapted to deliver the successive cans into the path of the revolving can hooks 12. The can hooks 12 cooperate with the fixed guard 60 to transport the successive cans 55 beneath the pockets 7 during filling, and a rotary can discharge disk 30 cooperates with an adjustable guide 54 to deliver the filled cans from the machine.

The improved motion transmitting mechanism for driving the various elements of the machine, is shown in detail in Figs. 1, 2 and 5. The main drive shaft 16 is rotatable in bearings secured to the main frame 28, being provided at one end with a hand wheel 26 and at its opposite end with driving and idler pulleys 17, 18 respectively. A driving belt which cooperates with the pulleys is shiftable from one pulley to the other by means of a shifter 27 which is adjustable from one side of the machine by means of a lever 19, and from the opposite side by means of a similar lever 25 which is connected to the shifter 27 by a connection 24.

The horizontal main shaft 16 carries a driving worm gear 120 which meshes with a gear 65 secured to a horizontal shaft 15 supported in the frame 28 and providing a support for the can feed drum 29. The shaft 15 also carries a gear 66 meshing with a gear 67 which drives the discharge disk 30, and has a grooved drum 14 secured to the medial portion thereof. A roller gear 13 secured to the main vertical shaft 11, has a series of rollers which cooperate with the groove of the drum 14 to produce intermittent rotation of the measuring pockets 7 during normal operation of the machine. The main shaft 16 also carries the worm which meshes with the gear 22 to produce rotation of the shaft 21 and gears 23, thereby operating the feeding fingers 6 in the manner previously described, during normal operation of the machine.

Other details of construction of the machine are similar to the corresponding details disclosed and more fully described in the copending applications hereinbefore referred to, and need no further specific description. It should be understood that the various elements are formed of material capable of most effectively resisting wear and corrosion due to the acid contained in the kraut juices.

During normal operation of the improved kraut filler, the kraut is delivered in bulk to the treating vat 33 wherein it is bleached, exhausted and sterilized, the individual fibres being segregated during such treatment. The kraut fibres are then removed from the tank 33 to the supply hopper 2, and a supply of liquor is constantly delivered to the tank 31 by means of the pump 38. The kraut admitted to the hopper 2 drops by gravity to the bottom of the chamber 4 and is gradually advanced toward the delivery opening 5 and is simultaneously gently compressed into a homogeneous dry mass, by

the oscillating fingers 6. The outermost fingers 6 are relatively remote from the next set thereby providing a rather large clear space for the kraut to settle through. The liquid which drains from the kraut in the chamber 4 passes through the slots 41 to the tank 33, and the kraut discharged through the opening 5 is delivered into one of the pockets 7 which is maintained in communication with the opening 5 until properly filled, and in which the plunger 8 is elevated as shown in Fig. 1. When the kraut receiving pocket 7 has been filled with fibre, it advances past the shearing knife 75 which operates to cut the fibres within the pocket from the mass within the chamber 4, without tearing the individual fibres. Immediately after receiving a charge of kraut fibre, the pocket 7 is placed into communication with the brine supply pipe 40 and tank 31 through the openings 68. Brine is then admitted and intermingles with the kraut to totally fill the pocket 7, whereupon the pocket advances about its axis of revolution and the measured batch is eventually discharged through the opening 70 into a can 55 located therebeneath. Each of the successive pockets 7 are supplied with fibre and juice in like manner, and the successive cans 55 delivered to and from the machine are filled with homogeneous and identical batches of mixture.

It will be noted from the foregoing description, that the various mechanism of the machine effectively perform their several functions, automatically. The combined bleacher, exhauster and sterilizer 33 places the material in proper condition and separates the individual kraut fibres from each other. When the mass of fibres is elevated and delivered into the feeding chamber 4, all of the entrained liquid is removed therefrom, and the production of equal batches of relatively dry kraut fibre is assured. The disposition of the feeding fingers 6, also insures uniform packing of the kraut as it passes through the chamber 4, and the shearing knife 75 effectively severs the measured batches from the bulk within the chamber 4 without undesirably damaging the kraut.

The passage 43 in the plungers 8 cooperating with the air vent 42, constitutes means for insuring proper filling of the measuring pockets 7 with homogeneous batches of kraut by insuring expulsion of air from within the pockets. The passages 43 and the slots 44 may be effectively cleaned by admission of steam through the pipe 74, such admission also serving to maintain the pockets 7 clean. By utilizing the modified plunger construction illustrated in Figs. 8 and 9, the maintenance of parallel motion for the plungers 80, is insured as the kraut juices cannot come in contact with the guide rods 71, 72 and thereby produce corrosion thereof. The

improved construction of the pistons or plungers 8 and of the member 48, specifically illustrated in Fig. 12, facilitates manufacture of these elements and enables proper fitting and guiding of the plungers 8. The lengths of the feeding fingers 6 may be varied to produce the desired fill, and the strokes of the plungers 8 may be likewise varied by means of the adjusting mechanism 46. The auxiliary can supports 69 may also be utilized when filling cans of different sizes.

It will also be noted that the improved driving and motion transmitting mechanism is relatively simple and compact in construction. The machine may be controlled by manipulation of either of the levers 19, 25, and may be operated manually by means of the hand wheel 26. The various elements of the structure are readily accessible for inspection, and the plungers 8 and the member 48 may be readily removed for cleaning.

It should be understood that it is not desired to limit the invention to the exact details of construction and to the precise mode of operation herein shown and described, for various modifications within the scope of the claims may occur to persons skilled in the art.

It is claimed and desired to secure by Letters Patents:—

1. In combination, a series of measuring pockets movable about an axis, a feeding chamber formed to compress material passing therethrough and being communicable with the successive pockets of said series, said chamber having openings for removing liquid from a mass of material passing through said chamber, and a plurality of movable fingers for urging fibrous material through said chamber and into said pockets.

2. In combination, a series of measuring pockets movable about an axis, a plurality of fingers movable to compress and rake fibrous material into the successive pockets of said series, means having openings for removing all liquid from the fibrous material during said raking, and means for subsequently mixing liquid with the fibrous material within said pockets.

3. In combination, a series of movable measuring pockets, a plurality of movable fingers for compressing and for urging fibrous material into the successive pockets of said series, and means providing a vent for effecting escape of air from said pockets during admission of said fibrous material thereto.

4. In combination, a series of measuring pockets movable about an axis, a plurality of fingers for compressing and for urging fibrous material into the successive pockets of said series, means having openings for removing all liquid from said fibrous material during movement thereof by said fingers, said means also providing a vent for effecting escape of air from said pockets during admission of said fibrous material, and means for

subsequently mixing liquid with the fibrous material within said sockets.

5. In combination, a series of measuring pockets, a plunger within each of said pockets, and a plurality of devices for compressing and for urging fibrous material into each of the successive pockets of said series, said plungers having vents for effecting escape of air from each of said pockets through said plungers and through a wall of said pockets during admission of fibrous material.

6. In combination, a series of measuring pockets movable about an axis, a plunger loosely fitting each of said pockets and movable therein during advancement of said pocket about said axis, a plurality of parallel guide rods located outside of said pockets for producing parallel movement of each of said plungers within its pockets, means for delivering fibrous material and liquid to each of said pockets, and means for delivering said materials from each of said pockets during a different stage of advancement thereof about said axis.

25 7. In combination, means forming a horizontally tapered chamber, a plurality of measuring pockets successively communicable with said chamber, means for delivering fibrous material into said chamber, and two sets of movable fingers projecting through each side of said chamber, the sets at one side being higher than those at the other and the path of movement of said sets overlapping each other.

35 8. In combination, a horizontally elongated chamber having opposite side walls, and a plurality of superposed sets of movable feeding fingers projecting into said chamber through each side thereof, the upper and lower sets of said fingers at one side of said chamber being higher than the corresponding sets at the opposite side thereof and the path of movement of said sets overlapping each other.

45 9. In combination, a series of measuring pockets movable about an axis, a plunger reciprocable within each of said pockets during advancement thereof about said axis, the cross-section of said plungers being substantially equal to that of said pockets, a plurality of parallel guides for producing parallel movement of each of said plungers within the corresponding pocket, means for delivering fibrous material and liquid to each of said pockets, and means for delivering said materials from each of said pockets during a different stage of advancement thereof about said axis.

55 10. In combination, a stationary annular wall having a cylindrical bore, a member rotatable within said bore, said member forming an annular series of measuring pockets, a plunger movable centrally within each of said pockets, and a pair of parallel guides secured to said member and coacting

with each of said plungers to insure parallel movement thereof within its pocket.

11. In combination, a series of measuring pockets movable about an axis, a plunger reciprocable within each of said pockets, and devices for compressing and for urging fibrous material into each of the successive pockets of said series, each of said plungers having a vent for permitting escape of air from the corresponding pocket through said plunger and through a wall of said pocket during admission of fibrous material.

12. In combination, a series of measuring pockets, a plunger movable within each of said pockets, devices for compressing and for urging fibrous material into each of the successive pockets of said series, said plungers having vents for permitting escape of air from each of said pockets through said plungers and through a wall of said pockets during admission of fibrous material, and means for preventing escape of fibrous material through said vents.

13. In combination, a series of measuring pockets movable about an axis, a plunger reciprocable within each of said pockets, devices for compressing and for urging fibrous material into each of the successive pockets of said series, each of said plungers having a vent for permitting escape of air from the corresponding pocket through said plunger and through a wall of said pockets during admission of fibrous material, and means for preventing escape of fibrous material through said vents.

14. In combination, a series of measuring pockets movable about an axis and having a common stationary wall enclosing a side thereof, a plunger movable within each of said pockets, and means for compressing and for urging fibrous material into each of said pockets in succession, each of said plungers having a vent communicable with a port in said wall to permit escape of air from the pocket during the admission of other material.

In testimony whereof, the signature of the inventor is affixed hereto.

OSWALD H. HANSEN.
